AUTOMATIC GRAIN WEIGHER

Filed June 26, 1923

2 Sheets-Sheet 2

UNITED STATES PATENT OFFICE.

GEORGE M. BAIRD, OF WICHITA, KANSAS.

AUTOMATIC GRAIN WEIGHER.

Application filed June 26, 1923. Serial No. 647,935.

To all whom it may concern:

Be it known that I, GEORGE M. BAIRD, a citizen of United States, residing at Wichita, county of Sedgwick, and State of Kansas, 5 have invented certain new and useful Improvements in Automatic Grain Weighers, of which the following is a specification, reference being had to the accompanying drawings, which form a part of this specification.

My invention relates to a grain weigher.

The object of my invention is to provide an automatic weighing mechanism that will weigh a continuous flow of grain from the 15 threshing machine.

Another object of my invention is to provide simple means for door adjustment and reinforcement for the door.

A further object of my invention is to 20 provide a weigher that the mechanical actions are very sensitive and positive in movement.

Referring to the drawings, Fig. 1 is a side elevation of weigher showing how it is attached to the elevator and spout. Fig. 2 is a front view, parts broken away for convenience of illustration. Fig. 3 is a fragmentary detail of the baffle plate. Fig. 4 is an enlarged detail view of door reinforcing 30 means.

1 is the elevator leg, 2 is the elevator head, connecting to said leg, and adapted to discharge into the weigher, said spout being funnelled as at 3, so as to throw the grain 35 within the opening of the weighing hopper. The weigher is composed of four walls 4, having a bevelled top as at 5, and extending inward forming a stop at 6, functioning as a stop for deflector valve 7, said de-

40 flector valve being riveted or welded to stop arms 9, said arms having a triangular loop end, for convenience of engaging in the notched ends of pawls 10 and the opposite ends of said rods being rigidly attached to a 45 cross shaft 11, by looping around said shaft, and having a pin 12 to cause said shaft to revolve in its oscillating motion, said shaft 11 is trunnioned in bearings 13, said bearings having a frame 14, which is rigidly attached

50 to side walls of weigher by means of rivets 15. On both ends of said rod 11 is securely fastened a segmental member D, to which are attached rods 16 and 16', said shafts having a curvature as at A, the object of 55 which is to adjust the length by bending means, the said rods 16 and 16' are placed

on both sides of the weighing hopper and extending downward and pivotedly mounted at 16, to door 17, said doors being hingedly attached to weighing hopper 4, at 18. 60

The said hopper being in two compartments, being divided by a partition 19, securely riveted to side walls and extending from the rod 11 downward, and terminating into a V shape as shown at 20, so that when 65 doors 17 are closed as shown at 17', the partition will engage with the bottom of the door as shown by dotted lines 21 in Fig. 4, by which means, when the door is closed as at 17', the grain remains in the 70 hopper until in the weighers descent, the door will open, causing the grain to discharge into a receptacle not shown and the cause of this mechanical movement will be 75 more fully described hereinafter.

The doors 17 and 17' are constructed of a sheet of metal with the ends turned upward, forming a flange as at B, and both sides being open with one edge hingedly attached to weigher as heretofore described, with 80 bottom member 22 fitting closely against the bottom edge of the hopper wall, and when closed the opposite of said door engages with the V or bevelled member 20, as shown at 21, and the sides B lapping on the outside of the hopper walls. The bottom 22 of said door is looped around a wire 23, providing a slant to said bottom as shown at C, tendency of which is to shoot the grain 85 slightly forward and also as means for reinforcing the edge of said bottom in conjunction with the L-shaped member 24, by which means the weight of the grain is not sufficient to spring along the edge of the 90 door.

The weighing hopper is hung to the scale beam by means of a strap 25, which is riveted securely to the hopper on both sides, the said strap 25 having an opening 26, adapted to engage over a scale blade 27, functioning as a pivot bearing, and in close proximity is a corresponding bearing as follows: To the scale beam 28 is riveted a member 29, extending downward and engaging the pivot points as heretofore described, and in said member 29 is an eye 30, engaging on a pivot blade 31, said blade being rigidly attached to the side of the lead, and the action of the scale beam and the hopper fulcrum on said blade 31, on the weight blade is placed 105 a weight for graduating purpose, said weight is not shown on the beam, but is 110

used to graduate the resistance required to weigh a certain quantity of the grain in equal measures in either one of the weighing hopper compartments of the said hopper, said hoppers being on either side of the partition 19 as heretofore described.

It will be understood that the scale beam is U shape, extending around to the opposite side of the head and connecting to the weigher and having pivot bearings as heretofore described. In Fig. 2 is shown, pivotedly mounted pawls 10, said pawls having notches 32, adapted to engage the stop member 9, the opposite ends of said pawls are pivotedly mounted at 33, and in opposite end of said pawl is an elongated opening 34, and through said opening a pin 35 is placed, as means for supporting said pawls, and to allow said pawls to raise when the stop member 9 is advancing to engage in the notch 32. The said pawls are pivotedly attached to a cross bar 36, the said bar being rigidly attached to head 2, and the said head and bar being stationary provides that when the weighing hopper descends by reason of the weight imposed therein, will cause the said stop 9 which travels with the descent of said hopper to disengage from notch 32, at which instant the weight being imposed on the door 17' as shown in Fig. 2 will cause said door to open by the revolution of the segmental member D, and prior to opening said door, the load is supported by rod A on the vertical axis of shaft 11 and by the purchase of this position, the door is easily held in a closed position, thereby reducing the tension of the stop member, which is engaged in notch 32, allowing it to slide easily out of engagement.

When my weigher is attached to the elevator head, and the threshing machine conveying the grain, the weigher will function as follows:

When the door 17' is closed as in Fig. 2, the grain is pouring from the head, striking the deflector valve 7, which delivers the grain into that side of the receptacle that the door is closed and when the required weight, as gauged by the scale beam is imposed, the hopper will drop, by reason of gravity, disengaging from the pawls, at which instant the weight of the grain will cause the door to open, and by which action the deflector valve will be reversed, immediately closing the opposite door and cause the grain to discharge in the opposite side and this motion will be automatically repeated, weighing the grain accurately on either side of the receptacle.

In the ascent and descent of my hopper, I have provided a looped member 37, which extends around conveyor 1 and said member being hingedly attached at 38, and said member 37, functioning as a bail will drop down over a hook 39, by which means, the

hopper is supported steadily in its ascent and descent.

Having thus described my invention, what I claim as new and desire to secure by Letters Patent is:

1. In an automatic grain weigher, of the kind described, a stationary elevator head, a scale beam, and pawls attached to the stationary elevator head, a two compartment hopper suspended from said scale beam, said hopper comprising an oscillating deflector valve, doors hingedly attached to the bottom of said hopper, rocker members and connecting rods, the said rods connecting the rocker members and doors, said rods attached in such a way that when one door is closed as by connecting rod 16', the point of connection of said rod to said rocker member will be near vertically positioned over the axis of the rocker member shaft 85 11, and by said position and angle of said rod will prevent locking on the center, said rocker members so formed that the downward movement of said door will be turned much slower on the beginning than the first 90 closing movement of the adjacent door, said doors reciprocating in their movement, for the purpose set forth and described.

2. In an automatic grain weigher, a stationary elevator head, pawls pivotally mounted on said elevator head, a scale beam, a two compartment hopper suspended from said scale beam, said scale beam having pivotal bearings spaced to accommodate for vertical movement to cause engagement and disengagement of a deflector valve stop, a stop mounted on said valve, said stop formed and adapted to engage with pivotally mounted pawls, said pawls being stationed on spout of elevator head, a deflector valve pivotally mounted by a shaft at the top of the partition between said hopper compartments, a rocker member mounted on each end of said shaft 11, connecting rods pivotally connected to said rocker members, and pivotally connected to said doors, the said deflector valve being actuated by the reciprocating movement of said doors, all for the purpose set forth and described.

3. In an automatic grain weigher, an elevator, a spout, a scale beam extending around said spout, means for suspending a grain container, means for pivotally mounting said scale beam, a grain container, means for steadyng said container to said elevator in the ascent and descent of said container, a partition in said container, a deflector valve plate, pivotally mounted at the top of said partition and the lower edge of said partition slanting in opposite direction to conform to the position of doors, a door under each compartment hingedly attached and actuated by rods, said rods having an off set or curvature for length adjustment, said doors being operated alter-

- nately by the action of each other, and said movement controlled by the weight of the grain as a motive element when said container descends disengaging said stop, a pair 5 of bars functioning as pawls, said bars being pivotally mounted so that the stop engaging ends may ratchet, dispensing the grain alternately for the purpose set forth and described.
- 10 4. In an automatic grain weigher, an elevator, a head, a scale beam pivotedly mounted on said head, a grain receptacle pivotedly depending from said beam, a bail hingedly attached to said elevator and also attached 15 to said weighing hopper, a pair of doors, hingedly attached to bottom of said weighing hopper, said doors having a bevel on one edge and an L shape on the opposite side, and wire interposed between said 20 shapes as reinforcing means, a shaft pass-
- ing through said weighing hopper, functioning as a trunnion, segmental member attached to ends of said shaft, rods pivotedly mounted to said segmental member and to said doors, so that by oscillation the said doors move in opposite directions alternately and the said rods having a bend as length adjusting means, a deflector valve firmly attached to said trunnion shaft, said valve having a stop member and said valve adapted 25 to engage with the bevel top of weighing hopper as at 6, a pair of pawls, pivotedly mounted and said pawls in close proximity adapted to engage said stop in its alternating movement, said movement created by 30 the downward movement of said weighing hopper, when said weighing hopper receives the proper weight for disengaging said stop, all for the purpose set forth and described.

GEORGE M. BAIRD.
